UNITED STATES PATENT OFFICE.

CLARA E. HOSMER, OF AUBURN, NEW YORK.

LEGGIN.

SPECIFICATION forming part of Letters Patent No. 320,557, dated June 23, 1885.

Application filed December 8, 1884. (No model.)

To all whom it may concern:

Be it known that I, CLARA E. HOSMER, of the city of Auburn, Cayuga county, New York, have invented certain new and useful Im-
5 provements in Leggins, of which the following is a full, clear, and exact description, reference being had to the accompanying drawing, forming part of this specification.

My invention relates to leggins made in the usual manner and of any of the usual materials of which such articles are made; and this invention relates, particularly, to the means employed to secure such leggins in position when worn. This I do by means of buttons, hooks, or buckles in the usual manner for about one-third of its length from the bottom of the leggin, and to secure the remaining upper part I employ a piece of elastic cloth, $a a' a'' a'''$, which is sewed or otherwise secured along its side $a a'$ to the part A' of the leggin, and along its side $a'' a'''$ to the part A. Within a tuck around the top of the leggin an elastic band, b, lies, and its ends are buckled, buttoned, or otherwise secured together at the desired length. This band assists in holding the leggin in position, and the lower end of the leggin may be held down to its proper position by means

of the loops c and d, which pass under the instep. The lower end of the part A is pro- 30 longed, as shown at g, to cover the instep, although I do not consider this essential.

By means of my invention a leggin may be applied and secured in position very readily and with particular closeness and ease of fit. 35

The flaps or edges of the parts A and A' may cover the elastic cloth $a a' a'' a'''$, though it is not necessary that they should; still I consider that the best arrangement when they do.

Buttons, hooks, buckles, or any equivalent 40 device or devices may be used at f f without changing the character of this invention, as well as upon the band b.

Having thus described my invention, what I claim as new, and desire to secure by Letters 45 Patent, is—

As an improved article of manufacture, a leggin having its opening closed by the elastic portion $a a' a'' a'''$, the buttons f, or their equivalents, and the elastic band b, all ar- 50 ranged substantially as set forth.

CLARA E. HOSMER.
